(57) **ABSTRACT**

A new and distinct *Pelargonium* plant with semi-double,
deep red colored flowers and a mounded habit.

1 Drawing Sheet

1

Botanical classification: *Pelargonium zonale* x *P. peltatum* interspecific hybrid.
Varietal denomination: 'PacPX18593'.

BACKGROUND OF THE INVENTION

The present invention comprises a new and distinct *Pelargonium* variety having the varietal name 'PacPX18593' and a botanical classification of *Pelargonium zonale* x *P. peltatum* interspecific hybrid. The new variety was discovered and selected in a planned breeding program in Dresden, Germany in the spring of 2018. The purpose of the breeding program was to develop interspecific *Pelargoniums* with a deep red flower color and moderate growth. The new variety is the result of crossing a bulk of different genotypes in the summer of 2017 in Dresden, Germany to obtain the applied-for variety. As such, the true parentage is unknown. The new variety was first asexually reproduced in January of 2019 by cuttings in Dresden, Germany. The new variety has been trial and field tested and has been found to retain its distinctive characteristics and remain true to type through successive propagations.

The new variety is similar to 'Pactiodare' (U.S. Plant Pat. No. 32,912) in having a mounded plant shape and vigorous growth habit with red-colored flowers. However, 'Pactiodare' exhibits single, self-cleaning flowers with no petaloids present. The following characteristics further distinguish the new variety from other *Pelargonium* varieties known to the breeder:

Early and plentiful flowering;
Semi-double flowers with a deep red color; and
Medium mounding habit.

DESCRIPTION OF THE DRAWING

The accompanying photographic drawing illustrates the new variety at approximately 4 months of age, with the color being as nearly true as is possible with color illustrations of this type.

DESCRIPTION OF THE PLANT

The following detailed description sets forth the characteristics of the new cultivar. The data which defines these

characteristics were collected from asexual reproductions and carried out in a greenhouse from spring through fall in Thiendorf, Germany. The new variety was grown in a 19.0 cm pot, with treatment of Cycocel® 720 0.2% two times, and no pinching or photoperiodic treatments. The average day temperatures were 18° C. and the average night temperatures were 16° C. The readings and measurements were taken on plants at approximately 8-9 months of age under a light level of 15-100 k lux. Color references are primarily to the 1995 edition of The R.H.S. Colour Chart of The Royal Horticultural Society of London, except where terms of ordinary color significance are used.

PLANT

- 15 Time to initiate roots (days, temperature): From 18-22 days at about 18-20° C.
- Time to develop roots (days, temperature): About 28 days at about 18-20° C.
- 20 Time to produce a finished flowering plant from a rooted cutting: About 70 days in a 13 cm container.
- Type: Potted annual. Possibly a perennial in frost-free environments.
- Root description: Dense, thin, fibrous, white, and freely branching.
- 25 Form: Mounded.
- Height from media surface to top of foliage: 34.0 cm.
- Height from media surface to top of flowers: 25.0 cm.
- Plant diameter: 45.0 cm.
- 30 Vigor: Strong with a fast growth rate.
- Branching:
- Type*.—Basal.
  - Primary branches*.—7.
  - Secondary branches per primary*.—5.
  - Lateral branch length*.—20.0 cm.
  - Lateral branch diameter*.—10.0 mm.
  - Internode length*.—1.5 cm.
  - Stem appearance*.—Rounded in diameter.
  - Stem aspect angle*.—Narrow.
  - Stem strength*.—Strong.

<i>Stem color.</i> —Developing: 146B. At internodes: 146B. Developed: 152A.		<i>Width.</i> —Upper petals: 19.0 mm. Lower petals: 22.0 mm.
<i>Luster.</i> —Semi-glossy.		<i>Shape.</i> —Obovate.
<i>Pubescence.</i> —Present.		<i>Apex shape.</i> —Round.
<i>Foliage:</i>	5	<i>Base shape.</i> —Pointed.
<i>Arrangement.</i> —Mainly opposite.		<i>Margin.</i> —Entire with low undulation.
<i>Type.</i> —Single.		<i>Texture.</i> —Smooth with no rugosity (both surfaces).
<i>Size of leaf.</i> —Length: 4.6 cm. Width: 6.8 cm.		<i>Luster.</i> —Glossy (both surfaces).
<i>Shape of leaf (generally).</i> —Round.	10	<i>Upper surface color.</i> —When opening: Close to 45A. Fully opened: Close to 45A. Fading: 45A. Venation: Close to 45A, and 58A at the marking.
<i>Shape of apex.</i> —Round.		<i>Lower surface color.</i> —When opening: Between 45A and 57A. Fully opened: Between 45A and 57A. Fading: 45D. Venation: 45A.
<i>Shape of base.</i> —Open.		
<i>Margin type.</i> —Shallow-lobed and crenate.		
<i>Sinus orientation.</i> —Divergent.		
<i>Texture.</i> —Leathery and slightly rough (both surfaces).	15	
<i>Luster.</i> —Upper surface: Matte. Lower surface: Semi-glossy.		
<i>Pubescence.</i> —Present (both surfaces).		
<i>Color.</i> —Young leaves: Upper surface: Close to 147A. Lower surface: 147B. Mature leaves: Upper surface: 20 Close to 147A. Lower surface: 147B.		
<i>Veins.</i> —Venation type: Palmate. Color: Upper surface: Close to 147A. Lower surface: 144A.		
<i>Petiole.</i> —Length: 5.5 cm. Diameter: 2.0 mm. Texture: Rough. Luster: Semi-glossy. Strength: Medium. 25 Color: 147B.		
<i>Stipules.</i> —Length: 10.0 mm. Width: 8.0 mm. Texture: Pubescent. Color: 144A.	30	
INFLORESCENCE		
<i>Bud:</i>		
<i>Shape.</i> —Elliptic.		
<i>Length.</i> —10.0 mm.		
<i>Width.</i> —6.0 mm.	35	
<i>Texture.</i> —Pubescent.		
<i>Luster.</i> —Matte.		
<i>Color.</i> —148A.		
Natural flowering season: April until frost in moderate climates.	40	
Arrangement: Inflorescence; umbel.		
Flower type and form: Zygomorphic; flat.		
Inflorescence height: 5.5 cm.		
Inflorescence diameter: 12.0 cm.	45	
Aspect: Upright.		
Flowering habit: Free.		
Number of flowers per inflorescence: 20.		
Average time to flowering: 70 days.		
Longevity on the plant:		
<i>Umbel.</i> —3-4 weeks.	50	
<i>Single flower.</i> —6-10 days.		
Persistent or self-cleaning: Persistent.		
Floral bracts: Absent.		
Flower:	55	
<i>Shape.</i> —Round.		
<i>Height.</i> —60.0 mm.		
<i>Diameter.</i> —55.0 mm.		
<i>Depth.</i> —15.0 mm.		
Petals:	60	
<i>Arrangement.</i> —Semi-double.		
<i>Number per flower.</i> —7.		
<i>Number of whorls.</i> —1.		
<i>Fused.</i> —No.		
<i>Length.</i> —Upper petals: 31.0 mm. Lower petals: 28.0 65 mm.		

Fragrance: None.

Keeping quality: 20 days.

Disease/pest resistance: Unknown.

Temperature tolerance: From 0-40° C.

Drought/rain/wind tolerance: Moderate.

Fruit/seed: None observed.

REPRODUCTIVE ORGANS

Stamen:

Number (per flower).—10.

Filament.—Length: 7.0 mm. Color: White.

Anther.—Shape: Short tube. Length: 2.0 mm. Width: 1.0 mm. Color: 187A.

Pollen.—Color: 187A. Amount: Moderate.

Pistil:

Number.—1.

Length.—8.0 mm.

Style.—Length: 2.0 mm. Color: 58A.

5 Stigma.—Shape: Actinomorphic, 5-parted. Diameter: 3.0 mm. Color: 58A.

Ovary color.—139D.

10 I claim:

1. A new and distinct variety of *Pelargonium* plant named 'PacPX18593', as is herein illustrated and described.
